UNITED STATES PATENT OFFICE.

WILLIAM S. ELLIOTT, OF PITTSBURGH, PENNSYLVANIA.

STRAINER.

1,380,114.

Specification of Letters Patent. Patented May 31, 1921.

Application filed October 31, 1918. Serial No. 260,457.

To all whom it may concern:

Be it known that I, WILLIAM S. ELLIOTT, a citizen of the United States, residing at Pittsburgh, in the county of Allegheny and 5 State of Pennsylvania, have invented a new and useful Improvement in Strainers, of which the following is a full, clear, and exact description, reference being had to the accompanying drawings, forming part of 10 this specification, in which—

Figure 1 is an end elevation of a strainer embodying my invention.

Fig. 2 is the same partly in side elevation and partly in vertical section, and

15 Fig. 3 is a section on the line III—III of Fig. 2.

My invention has relation to strainers for use in water supply or circulating systems and is designed to provide a strainer of the 20 type having removable strainer elements with means of simple and effective character for preventing dirt and the like being carried back into the supply side of the system while the normal operation of the 25 strainer is interrupted for the purpose of removing and cleaning the elements. My invention also provides a strainer of this type with means whereby the foregoing result may be obtained without entirely preventing the flow of water through the 30 strainer. It also provides means whereby dirt or the like is prevented from being carried through the strainer system into the pipe line while the strainer elements are 35 removed.

The nature of my invention will be best understood by reference to the accompanying drawings in which I have shown a preferred embodiment thereof and which will 40 now be described, it being premised, however, that various changes can be made in the details of construction, arrangement and combination of the various parts without departing from the spirit and scope of my 45 invention as defined in the appended claims.

In these drawings, the numeral 2 designates the casing of the strainer proper, 3 an inlet connection secured to one end of the casing 2, and 4 an outlet connection secured 50 to the opposite end of the casing 2. While I have shown the parts 2, 3 and 4 as separately constructed, I do not limit myself to this feature since, especially for smaller

sizes, it is obvious that these three parts might be cast in a single piece. 55

The casing 2 is formed at one side with removable doors 5 to permit access to the strainer chamber 6, which are secured in place by any detachable fastenings such as the bars 7. 8 designates strainer elements 60 which are removably supported in any suitable manner within the chamber 6, and which may be of any desired type. In the construction shown, these elements are in the form of cylindrical baskets of perforated 65 sheet metal whose supporting frames 9 are slidably mounted in guides 10 on the interior of the casing. When the doors 5 are removed the baskets can be readily taken out through the door openings for cleaning 70 and the like.

11 designates two oppositely located guard plates which are secured to the shafts 12 journaled in the inlet end portion of the casing 2. These guards consist of a suitable 75 frame to which are secured a perforated metal plate 13. When the guards are in open position, as shown in full lines in Fig. 3, they are within lateral offset portions of the inlet passage, and out of the path of the 80 flow of water through such passage. By actuating the shafts 12, these guards may be swung downwardly to the positions indicated in dotted lines in Fig. 3 whereby they extend across the entire inlet passage 85 adjacent to the inlet ends of the strainer elements.

In the operation of strainers of this general type, when it is desired to remove the strainer elements, the normal flow of water through the strainer is interrupted either 90 by stopping the pump which supplies the system and which is connected to the inlet end of the strainer; by breaking vacuum by opening the doors 5; or by valve means located between the supply and 95 strainer. When this occurs it is desirable to prevent dirt and the like from being carried from the strainer chamber back into the supply pipe by the reverse flow or eddy which is apt to then occur. While the baskets are removed it is also desirable to prevent dirt or foreign material from being carried through the strainer chamber. It is for these purposes that the guards 11 are provided. When in their closed positions, 100 they effectively guard against the passage

of dirt and the like either from the supply line into and through the strainer chamber or from the strainer chamber back into the supply line. At the same time the perforations in the guards are of sufficient capacity so that the flow of water is not entirely interrupted.

The shafts 12 may be actuated in any suitable or convenient manner. In the construction shown I have provided the shaft 14 journaled at the outer side of the casing 2 at one end and carrying two worms 15 which mesh respectively with the teeth of the segments 16, which are fastened to the projecting end portions of the shafts 12. The shaft 14 is provided at one end with a hand wheel 17.

It will be understood that the guards provided by my invention are entirely independent of and additional to any valves which may be provided for controlling the flow through the strainer.

The advantages of my invention will be apparent from the foregoing. The guards are entirely within the strainer structure in both their open and closed positions; they in no way interfere with the normal flow through the strainer, and can be quickly moved into and out of their operative positions.

I claim:

1. A strainer apparatus comprising a strainer chamber having a single flow entrance passage, a strainer element removably seated in said chamber, and a perforated guard device normally supported in a position outside the line of flow through said flow passage and arranged to be moved across said passage in series with the strainer element, substantially as described.

2. A strainer comprising a casing having a strainer chamber, an inlet connection and an outlet connection, a plurality of strainer elements removably seated in said chamber, and pivoted guard members arranged to be moved into and out of position across the inlet passage adjacent to the strainer elements and normally supported

in a position outside of the line of flow through said chamber, substantially as described.

3. A strainer comprising a casing having a strainer chamber, an inlet connection and an outlet connection, a strainer element removably seated in said chamber, and pivoted guard members arranged to be moved into and out of position across the inlet passage to said chamber, said guard members having perforations therethrough and normally supported in a position outside of the line of flow through said passage, substantially as described.

4. A strainer comprising a strainer chamber having inlet and outlet connections, a strainer element seated in said chamber, a perforated guard member normally contained within the inlet connection and movable to a position across the inlet end of said element, said guard member being normally supported in a position outside of the line of flow through said connection, substantially as described.

5. A strainer, comprising a casing having a strainer chamber and an inlet connection, said inlet connection having its inlet passage provided with laterally offset portions, and pivoted guard devices normally lying within said offset portions and outside of the line of flow through said connection and movable downwardly across said passage, substantially as described.

6. A strainer, comprising a casing having a strainer chamber and an inlet connection, said inlet connection having its inlet passage provided with laterally offset portions, and pivoted guard devices normally lying within said offset portions and normally outside of the line of flow through said connection and movable downwardly across said passage, together with means for simultaneously actuating said members, substantially as described.

In testimony whereof, I have hereunto set my hand.

WILLIAM S. ELLIOTT.
